UNITED STATES PATENT OFFICE

GLENN ALBERT PRITCHETT, OF RENO, NEVADA

EXPLOSIVE

Application filed January 29, 1932. Serial No. 589,704.

My invention relates to explosives, and contemplates the production of a series of explosive mixtures or compounds of mutually different characteristics and uses, all of which 5 however possess in common certain novel features and properties. The invention also contemplates a novel method of compounding explosives.

Principal objects of the invention are to 10 provide a superior and inexpensive explosive product which will be free from certain serious disadvantages of explosives of the prior art hereinafter briefly indicated.

The invention includes the use of dinitrotoluene of approximately a freezing point 15 which has not been used in the manufacture of explosives prior to my present invention. The novelty of my invention also resides principally in the elimination of certain ingredients heretofore regarded as necessary 20 to the production of explosives of comparable grade, and in certain novel features of the processing of the ingredients, all of which will hereinafter be more particularly described and claimed.

The invention contemplates several varying formulæ, each formula providing an explosive of different grade and influence. Dinitrotoluene is used in each formula. 30 This material is commercially obtainable in various grades characterized by different freezing points ranging from about 25° C. to 65° C. I have found it necessary to use DNT having a freezing point not lower than 35 40° C. in order that the material may exist in a crystalline condition in the product.

The lowest grade explosive contemplated by my invention contains the following ingredients:

Formula A

Per cent

Dinitrotoluene	10
Sodium nitrate	90

45 The sodium nitrate is sized between 8 and 18 mesh and thus introduced into the composition in relatively granular form, as distinguished from the pulverulent state in which this material has been used heretofore.

50 The nitrate grains used in Formula A are

such as pass an 8 mesh sieve and are retained on an 18 mesh sieve. Consequently, none of the grains are larger than 8 mesh and none are smaller than 18 mesh. The curve on the accompanying graph, hereinafter referred to, 55 indicates the average size. I consider the proper sizing of the nitrate important and conducive to the improved efficiency of the resulting product.

The DNT is warmed to a temperature 60 above its melting point, say 60° C. for average material, and mixed with the nitrate. The mixture is maintained above the melting temperature of the DNT during the mixing operation to prevent crystallization of the 65 liquid until an intimate mixture is obtained.

Upon cooling, the DNT adheres as an oily coating to the nitrate grains, protecting the nitrate from moisture, and minimizing friction. Each grain of the product is an independent explosive agent, combustion being 70 transmitted from one grain to another when the mixture is set off. The relatively coarse character of the granular product prevents the explosive becoming dense and insensitive 75 to the influence of detonators when packed tightly in machine loaded cartridges or tamped in blast holes.

The explosive product is solid at ordinary 80 atmospheric temperatures. Disintegration and separation of constituents cannot therefore occur, and the efficacy and safety of the product are not affected by ordinary climatic changes. The explosive composition is superior in "strength" to ordinary black blast- 85 powder and is comparable thereto in cost of production and safety in handling.

My product is equal in all respects to prior art explosives including relatively expensive sodium chlorate, which it has heretofore been 90 thought necessary to use in an amount equal to at least 25% of the total weight of all ingredients in order to produce complete combustion when even the best detonator is employed.

An important object of the invention is to 95 produce an explosive compound which will not pack densely, and to this end DNT is selected having a freezing point directly related to the size of the nitrate grains. The larger 100

the grain, the higher may be the freezing point of the DNT, and, conversely, when relatively small grained nitrate is used, DNT having a lower freezing point is used. On 5 the annexed drawing, which forms part of this application for Letters Patent, there is plotted a curve showing the ratio of grain size to DNT freezing points between 8 and 50 mesh and 65° and 25° C. The thickness of the 10 curve indicates the amount of variation in the ratio of grain size and freezing point which may be practiced without materially sacrificing the benefits obtained by strictly observing the ideal ratios. Thus, it will be noted 15 that the ratio of DNT freezing point and nitrate grain size given for Formula A by way of example may be more or less departed from, especially by using DNT of a higher freezing point, since the nitrate grains in 20 Formula A are large enough to prevent density of pack in the product. It may, however, be stated that with nitrate grains of the size prescribed for Formula A, the freezing point of the DNT should not be lower 25 than 40° C. It is important that the DNT be in the frozen state in the product, and the smaller the grains the less solidly frozen must be the DNT. Otherwise the product 30 packs densely and becomes relatively insensitive to the action of ordinary fuse caps or electric exploders.

When substantially the ratio prescribed is followed a satisfactory low grade explosive compound is produced which is slightly 35 higher in percentage of strength than ordinary black blasting powder, which will detonate consistently with No. 6 fuse caps or electric exploders, and which possesses resistance to friction, fire and impact superior to any 40 other comparable explosive of which I am aware.

To provide a more quickly burning and stronger explosive, having otherwise all the 45 advantages of the physical property of Formula A, I replace some of the nitrates of the formula with other ingredients, including a chlorate, as follows:

Formula B

	Per cent
Dinitrotoluene	10
Sodium nitrate	73
Sodium chlorate	15
Lime	.5
Wood pulp	1.5

In the compounding of this formula the DNT and the nitrate are treated as in Formula A. The chlorate and the lime are ground to pass a 50 mesh screen, while the wood pulp is ground to 8 mesh.

In Formula B the chlorate steps up the rate of combustion and consequently increases the strength of the product; the lime 65 serves to neutralize any active acid which may be present in the mixture; and the wood

pulp provides carbon and serves to absorb and retain any excess oil.

A still stronger explosive is provided by further increasing the proportion of chlorate, as follows:

Formula C

	Per cent
Dinitrotoluene	11
Sodium nitrate	56.5
Sodium chlorate	30
Lime	.5
Wood pulp	2

In Formula C I prefer to use smaller sized nitrate grains e. g., such as sieve between 10 and 20 mesh. To illustrate the latitude permissible in the ratio of DNT freezing point and nitrate grain size, it may be stated that with nitrate grains so slightly reduced in size compared with those of Formula A, the DNT may be of the same freezing point as that prescribed for Formula A, since in Formula C the nitrate grains are still large enough to prevent density of pack in the product.

A still stronger product is given by the following formulæ:

Formula D

	Per cent
Dinitrotoluene	10
Sodium nitrate	41
Sodium chlorate	39.5
Lime	.5
Wood pulp	8
Mononitrotoluene	1

Formula E

	Per cent
Dinitrotoluene	10
Sodium nitrate	44
Sodium chlorate	39.5
Lime	.5
Bagasse flour	5
Mononitrotoluene	1

These two formulæ produce products substantially equal in strength, Formula E being desirable where it is necessary to consider oxygen balance in the product and a lower carbon content is required. Bagasse flour has almost twice the absorbent qualities of wood pulp, so that a smaller quantity may be used.

In Formulæ D and E the nitrate grains are sized at not larger than 20 mesh. Such reduction in grain size necessitates using DNT of a lower freezing point, to prevent density of pack, and to this end a small proportion of mononitrotoluene is added to the DNT. The freezing point of the mixture of the two toluenes in Formulæ D and E should be not higher than 37° C.

In each formula the moisture content is less than 1%.

It is to be understood that the five formulæ set out hereinabove are given merely by way of example of several embodiments of the invention. It will be understood of course that

an indefinite number of other formulæ are contemplated by the invention, when explosives of varying strengths are desired, all exemplifying the characteristic ratio of toluene 5 freezing point and nitrate grain size. Furthermore, slight departures from the proportions of ingredients, temperatures, and grain sizes specifically set out in the specification and appended claims are considered within 10 the spirit of the invention and within the scope of the claims.

I claim:

1. An explosive including DNT and sodium nitrate in which the DNT has a freezing point not lower than 40° C., and the 15 grains of nitrate are sized between 8 and 18 mesh, and in which the DNT is carried as a coating on the nitrate grains.
2. An explosive as claimed in claim 1, 20 which contains substantially 10 parts of DNT and 90 parts of sodium nitrate.
3. An explosive as claimed in claim 1 which contains substantially 10 parts of DNT, 73 parts of sodium nitrate and 15 parts of sodium 25 chlorate.
4. An explosive as claimed in claim 1 which contains substantially 10 parts of DNT, 41 parts of sodium nitrate and 39.5 parts of sodium chlorate.
5. An explosive including DNT and sodium nitrate in which the freezing point of the DNT and the grain size of the sodium nitrate are related as follows: for nitrate 30 grain sizes above 50 mesh to approximately 14 mesh the freezing point of the DNT varies directly with the grain size between substantially 25° C. and substantially 41° C., and for nitrate grain sizes above 14 mesh to approximately 8 mesh the freezing point of the 35 DNT varies directly with the grain size between substantially 41° C. and substantially 65° C.
6. The method of compounding an explosive containing DNT and sodium nitrate including the step of admixing DNT and sodium nitrate having the following relation: for nitrate grain sizes above 50 mesh to approximately 14 mesh the freezing point of the DNT varies directly with the grain size 40 between substantially 25° C. and substantially 41° C., and for nitrate grain sizes above 14 mesh to approximately 8 mesh the freezing point of the DNT varies directly with the grain size between substantially 41° C. and substantially 65° C.

In testimony whereof I affix my signature.
GLENN ALBERT PRITCHETT.
